UNITED STATES PATENT OFFICE

HENRY DREYFUS, OF LONDON, ENGLAND, AND CLIFFORD IVAN HANEY, OF DRUMMOND-
VILLE, QUEBEC, CANADA, ASSIGNORS TO CELANESE CORPORATION OF AMERICA,
A CORPORATION OF DELAWARE

MANUFACTURE OF ALIPHATIC ANHYDRIDES

Application filed June 15, 1928, Serial No. 285,614, and in Great Britain July 15, 1927.

This invention relates to the manufacture of aliphatic anhydrides from aliphatic acids and especially to the manufacture of acetic anhydride from acetic acid.

5 It is known that aliphatic anhydrides can be produced by passing aliphatic acid vapour through tubes or other apparatus heated to high or relatively high temperatures. In such processes however, we have found that, 10 especially after continued operation of the process at high temperatures, a certain amount of charring or decomposition to gaseous products takes place.

We have now found that this difficulty can 15 be largely or entirely overcome if the aliphatic acid vapour is subjected to pyrogenic reaction by mixing it with an inert gaseous medium heated to temperatures above those at which the aliphatic acid vapour is split to 20 anhydride and water.

According to the invention therefore we produce aliphatic anhydrides (and especially acetic anhydride) by mixing aliphatic acid vapour (and especially acetic acid vapour) 25 with an inert gaseous medium heated to temperatures above those at which the aliphatic acid is split to anhydride.

In performing the invention we may employ any inert gaseous medium, for instance, 30 nitrogen, hydrogen, steam or superheated steam, the last mentioned being especially suitable.

The splitting of the aliphatic acid vapour to anhydride by the process of the invention 35 may be performed at any temperatures above the point of splitting of the aliphatic acid to anhydride, for instance at temperatures of from about 500° to 1200° C. and preferably 500° to 1000° C., and for this purpose the 40 inert gaseous medium may, prior to admixture with the aliphatic acid vapour, be heated to any temperature above the point of splitting of the aliphatic acid to anhydride, for instance to temperatures of from 45 about 600° to 1200° C. and preferably 800° to 1200° C.

The aliphatic acid vapour may be mixed 50 with the heated inert gaseous medium in any suitable manner; for instance, the aliphatic acid in liquid or vapour form,

and preferably in vapour form, may be injected into a stream of the heated inert gaseous medium, or for instance a stream of the acid vapour and a stream of the heated inert gaseous medium may each be passed into a vessel which is preferably provided with baffles or the like to ensure good mixing.

The aliphatic acid vapour, prior to being mixed with the heated inert gaseous medium, may with advantage be preheated to any temperature below that at which the splitting of the aliphatic acid vapour is to be performed. For instance, when the splitting of the aliphatic acid vapour is to be performed at temperatures over about 600° C. the aliphatic acid vapour may with advantage be preheated to about 150° to 300° C.

The gases or vapours resulting from the admixture of the aliphatic acid vapour with the inert gaseous medium, and hereinafter referred to as the reaction vapours, may be treated in any suitable way to recover the anhydride produced. In order to obtain the highest yield of anhydride care should be taken to avoid condensation of the water vapour (present or produced by the reaction) with the anhydride, as if such condensation takes place the anhydride is to a greater or less extent hydrolyzed back to the acid with resulting diminution of yield of anhydride.

To avoid such condensation and to obtain the anhydride in as pure a form as possible the reaction gases or vapours may be subjected to fractional condensation, for instance by leading them upwards through one or more fractionating columns maintained at a temperature or temperatures intermediate between the boiling points (under the conditions of pressure obtaining) of water and of anhydride whereby the anhydride is condensed and the water passes on in vapour form. Or the reaction vapours may be passed through a solvent or mixture of solvents for the anhydride which have higher boiling points than water, and preferably of higher boiling points than the anhydride, and which are preferably insoluble in water, such solvents being employed at temperatures intermediate between the boiling points (under the conditions of pressure obtaining) of wa-

ter and of the anhydride, whereby the anhydride is condensed or absorbed and the water escapes in vapour form. As examples of such solvents may be mentioned chlorbenzols, 5 benzylether, tetrachlorethane, acetyl glycerins, anisol, acetylresol, benzylethers, phenetol, paraffin oil or mixtures of two or more of such bodies.

Or the reaction vapours may for instance be 10 subjected to condensation by the process described in our British Patent No. 303,772 and the corresponding U. S. application S. No. 284,566 filed June 11, 1928. That is to say the anhydride may be condensed from the reaction 15 vapours whilst carrying away the water vapour by the vapour of one or more entraining liquids. In such form of execution the reaction vapours are preferably mixed after leaving the hot reaction zone with the vapours of the entraining liquid or liquids at 20 a temperature below the boiling point (under the conditions of pressure obtaining) of the anhydride. Conveniently such mixing may be performed by introducing the reaction 25 vapours (which should not be allowed to cool below the boiling point of water before becoming mixed with the vapours of the entraining liquid or liquids) into a vessel up which the vapours of the entraining liquid or liquids are caused to rise; by this means the anhydride may be substantially condensed and the water vapour carried away with the vapours of the entraining liquid or liquids.

Examples of entraining liquids which we 30 may use for such method of condensation are, as indicated in our said British Patent No. 303,772 and the corresponding U. S. application S. No. 284,566 filed June 11, 1928, benzene, carbon tetrachloride, petrol, mixtures of two or more of such bodies or mixtures of ether with petroleum ether, it will be understood however that any other liquids chemically inert to the anhydride and having a high entraining capacity for water may 45 be employed. The liquids should preferably have a low entraining capacity for the anhydride.

Or the reaction vapours may for instance be subjected to condensation by the process 50 described in our British Patent No. 298,667 and corresponding U. S. application S. No. 285,613 filed June 15, 1928, that is to say they may be subjected to condensation by leading them under the surface of an "extracting" 55 liquid cooled down or otherwise kept at temperatures below (and preferably considerably below) the boiling point of water. As explained in our said British Patent No. 298,667 and corresponding to U. S. application S. No. 285,613 by the term "extracting" liquid we mean a liquid or liquid mixture in which the anhydride is soluble and which is chemically 60 inert to the anhydride and insoluble or substantially insoluble in water. As examples of such "extracting" liquids may be men-

tioned benzene, chloroform and mixtures of ethylether or chloroform with one or more hydrocarbons such as light paraffins, gasoline, kerosene, benzol or its homologues. As stated in our said British Patent No. 298,667 and 70 corresponding to U. S. application S. No. 285,613, we preferably use as "extracting" liquids, liquids of the character referred to which are themselves hydrocarbons or which contain hydrocarbons, for example, benzene, 75 or mixtures of ethylether or chloroform with one or more hydrocarbons such as paraffins (particularly the petroleum fraction of boiling point 40° to 70° C. termed petroleum ether), gasoline (boiling point 70° to 90° C.), 80 kerosene, benzol or its homologues. The following particular examples of "extracting" liquids have been found to be very suitable:—ether in admixture with petroleum ether, chloroform mixed with petroleum ether 85 and/or gasoline; and mixtures of ether and petroleum ether containing about 30 to 50% of petroleum ether are especially suitable.

Or the reaction vapours may for instance be treated by the process described in the 90 British Patent No. 289,972 and the corresponding U. S. application S. No. 242,977 of 27th December, 1927, that is to say they may be passed over or otherwise in contact with one or more "water binding" substances 95 maintained at a temperature or temperatures below (and preferably substantially below) the temperature at which the splitting of the aliphatic acid vapour is performed. By such treatment the water vapour may be substantially absorbed from the reaction vapours.

In such treatment the water binding substances are preferably maintained at temperatures above the boiling point (under the conditions of pressure obtaining) of water 100 to avoid condensation of water and the resulting risk of loss of anhydride through hydrolysis, and for the best functioning of the treatment the water binding substances should be employed at temperatures above 105 the boiling point of the anhydride in which case the water can be substantially absorbed and the anhydride pass on in vapour form. As explained in the said British Patent No. 289,972 and the corresponding U. S. application S. No. 242,977 of 27th December, 1927 110 the term "water binding" substance means bisulphates, pyrosulphates (especially bisulphates and pyrosulphates of the alkali and earth alkali metals), zinc chloride, calcium chloride, orthophosphoric acid, pyrophosphoric acid, metaphosphoric acid and like substances which have affinity (and preferably high affinity) for water but excluding substances having a deleterious effect on aliphatic acids or anhydrides, such as sulphuric acid.

The accompanying drawing illustrates in diagrammatic form one form of execution of the invention, applied by way of example to 115

the manufacture of acetic anhydride from concentrated or glacial acetic acid, it being understood that they are given only by way of illustration and are in no way limitative.

5 Referring to the drawing the acetic acid is vaporized in the still 1 and the resulting vapours passed via the pipe 2 to the outer zone 3a of the heat exchanger 3, where they are heated to a temperature of about 200°-300° C., and pass thence via the pipe 4 into the reaction vessel 5 (of copper, earthenware, vitreosil or other suitable material) in which they are mixed with superheated steam supplied at a temperature of 800° to 1000° C.

10 15 by the pipe 6. The supply of the acetic acid vapour to the vessel 5 is controlled by the cock 7 to keep the temperature of the mixed vapours at 500° to 800° C. The vessel 5 is provided with baffles 8 to ensure thorough

20 25 mixing of the acid vapours with the superheated steam. The reaction vapours pass from the vessel 5 through the pipe 9 to the inner zone 3b of the heat exchanger 3 where they are cooled to about 200° to 300° C. The reaction vapours pass from the inner zone 3b of the heat exchanger 3 via the pipe 10 down below the surface of the "extracting" liquid (a mixture of ether and petroleum ether, for instance a mixture of equal volumes of ether and petroleum ether) 11 contained in a brine cooled or water cooled vessel 12, the end of the pipe 10 carrying a rose or jet 13 to ensure that the reaction vapours are delivered into the "extracting" liquid in a state of fine division. The reaction vapours, before passing under the surface of the extracting liquid may if desired be mixed with the vapours of the ether/petroleum ether mixture; for instance, after leaving the inner zone 3b of the heat exchanger 3 they may pass to a vessel (not shown) interposed in the pipe 10 and to which the vapours of the ether/petroleum ether are supplied. The temperature of the reaction vapours, immediately prior to coming in contact with the extracting liquid is kept at a temperature above the boiling point of water, for instance about 100°-150° C. The "extracting" liquid is kept at a temperature of about 20° C. by

30 35 40 circulation of cold water or brine through the jacket 14, and gentle stirring is applied to the "extracting" liquid by means of the stirrer 15 to ensure uniformity of temperature in the liquid and to ensure that fresh "extracting" liquid is brought in contact with the incoming reaction vapours. The reaction vapours on issuing from the jet or rose 13 become condensed and the anhydride is separated from the water to a very efficient

45 50 55 extent, the anhydride (together with unconverted acetic acid) dissolving in the "extracting" liquid whilst water falls to the bottom of the vessel 12 and runs off through the pipe 16. The vessel 12 is provided with an outlet pipe 17 and a constant level run off

18 and by this means the "extracting" liquid containing the dissolved anhydride, is run off continuously via the pipe 17 and constant level 18 into the receiver 19.

The water runs off from the vessel 12 through the pipe 16 and the pipe 20 to the run off vessel 21, and in so doing is scrubbed by an ascending stream of "extracting" liquid fed by gravity from the tank 22 via the pipe 23 and the nozzle 24. The "extracting" liquid issues from the nozzle 24 in the form of a fine spray and passes up through the pipe 20 in the form of small drops and thence via the pipe 16 into the vessel 12; for convenience of observation the pipe 20 is made of glass. By means of this scrubbing very little anhydride or unconverted acid is carried away by the water and the water can be run to waste from the run off vessel 21.

Instead of running the water off from the vessel 12 in the manner above described it may be run off in any other desired manner. For instance it may be run off continuously from the bottom of the vessel 12 by means of a Florentine bottle as commonly employed in the essential oil industry and in the manufacture of acetic anhydride.

The acetic anhydride may readily be recovered from the "extracting" liquid collected in the receiver 19, for instance the liquid so collected may be heated to distill off the "extracting" liquid.

It will be understood that the invention is not limited as to the strength of the aliphatic acid employed. The process can be performed even with the vapours of dilute acids; and besides affording a ready means for the manufacture of anhydride from concentrated or highly concentrated acids, it affords valuable means for producing anhydrides from waste or dilute acids, especially waste or dilute acetic acids such as result from the acetylation of cellulose or other industrial acetylation processes.

What we claim and desire to secure by Letters Patent is:—

1. Process for the manufacture of an aliphatic anhydride comprising subjecting an aliphatic acid vapor to pyrogenic decomposition by mixing it with an inert gaseous medium heated to a temperature above that at which the aliphatic acid vapor is split to its anhydride and water.

2. Process for the manufacture of acetic anhydride, comprising subjecting acetic acid vapor to pyrogenic decomposition, by mixing it with an inert gaseous medium heated to a temperature above that at which acetic acid is split to its anhydride and water.

3. Process for the manufacture of an aliphatic anhydride comprising subjecting the vapor of an aliphatic acid to pyrogenic decomposition by mixing it with superheated steam heated to a temperature above that at

which the aliphatic acid vapor is split to its anhydride and water.

4. Process for the manufacture of acetic anhydride comprising subjecting acetic acid

5. vapor to pyrogenic decomposition by mixing it with superheated steam heated to a temperature above that at which acetic acid is split to its anhydride and water.

6. Process for the manufacture of an aliphatic anhydride comprising subjecting the vapor of an aliphatic acid to pyrogenic decomposition at a temperature between 500°

7. and 1000° C. by mixing it with an inert gaseous medium heated to a temperature between 600° and 1200° C.

8. Process for the manufacture of acetic anhydride comprising subjecting acetic acid vapor to pyrogenic decomposition at a temperature between 500° and 1000° C. by mixing it with superheated steam heated to a temperature between 600° and 1200° C.

9. In a process according to claim 1, the step of heating the aliphatic acid vapor to a temperature below that at which the pyrogenic decomposition is to be performed prior to mixing the aliphatic acid vapor with the heated inert gaseous medium.

10. Process according to claim 1 and wherein in said vapor and said gaseous medium are mixed by passing them in regulated streams into a vessel provided with baffles.

In testimony whereof we have hereunto subscribed our names.

HENRY DREYFUS.

CLIFFORD IVAN HANEY.
